UNITED STATES PATENT OFFICE.

RAYMOND SWARTZ, OF HARRISBURG, PENNSYLVANIA.

REMOVABLE CONTACT TIP.

Application filed July 13, 1922. Serial No. 574,813.

To all whom it may concern:

Be it known that I, RAYMOND SWARTZ, a citizen of the United States, residing at Harrisburg, in the county of Dauphin and State of Pennsylvania, have invented certain new and useful Improvements in Removable Contact Tips, of which the following is a specification.

My invention relates to contact fingers for controllers or switching devices and more particularly to such fingers as are adapted to engage the contact ring segments of drum type controllers.

Contact fingers of the drum type of controllers are provided upon their free ends with contact or burner tips which are usually screwed or riveted to the finger. When the burner tip has become worn and is to be replaced considerable difficulty is experienced in removing the same when it is riveted to the finger since it is necessary that the contact finger be removed from the controller in order that the rivets may be driven out and a new tip riveted on. Where the burner tip is screwed upon the contact finger while the removal thereof is comparatively simple, yet the objection to this expedient is that after the tip has been upon the finger some time the screws work loose and the result is a poor contact between the burner tip and the contact finger. It is therefore the primary object of my invention to provide a novel and improved means whereby a contact tip may be removably secured to a contact finger for ready replacement when worn and which will maintain a good contact with the contact finger at all times.

A further object of the invention is the provision of a very simple contact tip securing means which is readily applicable to standard contact tips and fingers with but slight modification thereof, and which will effectually hold the contact tip in place upon the finger.

With the above and other objects in view as will become more apparent as the description proceeds, the invention comprises a novel combination and arrangement of parts to be hereinafter described and claimed, and in order that the same may be better understood, reference is had to the accompanying drawing, forming a part of this specification.

In the drawing,

Figure 1 is a plan view of a portion of a contact finger, the contact tip of which is secured in accordance with my invention;

Fig. 2 is a rear elevation thereof;

Fig. 3 is a central longitudinal sectional view on the line 3—3 of Fig. 2;

Fig. 4 is a detail in plan of the inner face 60 of the contact tip and,

Fig. 5 is a detail of the contact finger with the contact tip removed.

Referring specifically to the drawing, wherein like reference numerals designate 65 unlike parts throughout the several views, numeral 10 denotes a contact finger of the conventional type comprising the usual spring metal strips 11 with a plurality of relatively thin copper strips 12 therebetween. Since 70 the contact finger, per se, forms no part of the present invention a further description thereof is unnecessary.

Coming now to the subject matter of my invention, a transverse hole is drilled in the 75 free end of the contact finger 10 through which the threaded end of a bolt 13 freely passes carrying upon its inner or headed end a wedge-shaped member 14 upon which the burner tip 15 is supported. The side 80 edges of the wedged shaped member 14 are inwardly beveled as shown at 16 and the burner tip 15 is provided with a vertical wedge-shaped groove 18, for the reception of the member 14, the walls of said groove 85 being outwardly beveled as shown at 19 to conform to the inward bevel of the edges of the wedge-shaped member 14. It will thus be seen that when the reduced end of the wedged-shaped member is inserted in 90 the widened end of the groove 18 and driven upwardly that the contact tip 15 will be effectually held thereon with the widened end of the wedge-shaped member 14 serving as a support for the burner tip 15. The 95 member 14 may be soldered, riveted or secured upon the end of the bolt 13 in any other preferred manner. A spring washer and nut, 20 and 21 respectively, upon the free end of the bolt 13 rigidly hold the 100 wedge-shaped member to the contact finger. A portion of the contact drum of the controller is shown at 22 bearing the ring segment 23 against which the burner tips strike when the drum is rotated.

It will be noted that the thickness of the wedge-shaped member 14 is considerably less than the depth of the groove 18 of the burner tip 16 and that the width of said wedge-shaped member is approximately 110 equal to the back of said groove 18, the object of this construction being to draw the

inner face of the burner tip 16 firmly against the contact finger 10 to insure a good contact therewith.

From the foregoing description read in connection with the accompanying drawing, the novel features of my invention will be clear to those skilled in the art and the advantages thereof readily appreciated. When the burner tip 15 has become worn and a new one is required, it is only necessary that it be given a few taps upon its bottom edge with a hammer to loosen it from the member 14 whereupon it may be lifted off and a new tip slipped thereon. Both operations may be accomplished in a few seconds without the necessity of removal of the contact finger 10 from its position. Another mode of removing the burner tip is to loosen the nut 21 whereupon it may be slipped off and another put in its place after which the nut 21 will be tightened to draw the wedge-shaped member 14 with the burner tip 15 tightly against the contact finger 10.

While I have illustrated the wedge-shaped member 14 as being bolted to the contact finger 10, it will be understood that it may be riveted or otherwise secured thereto.

In accordance with the patent statutes I have described and illustrated the preferred embodiment of my invention but I do not propose to limit myself strictly thereto, since various modifications thereof will readily suggest themselves to those skilled in the art without departing from the spirit of my invention, the scope of which is set forth in the appended claims.

Having thus described my invention what I claim is new and desire to secure by Letters Patent is:

40. 1. The combination with a contact finger of a wedge-shaped member secured thereto, the side edges of said wedge-shaped member being inwardly beveled to the inner face thereof, and a burner tip carried by said wedge-shaped member and having a wedge-shaped slot upon its inner face, the side walls of which are outwardly beveled to the bottom thereof for the reception of said wedge-shaped member, the thickness of said wedge-shaped member being less than the depth of said slot, and the width of said wedge-shaped member approximating the width of said groove at the back thereof.
45. 2. The combination with a contact finger; of a support secured thereto, the side walls of said support converging in the direction of its length, a burner tip carried by said

support, said burner tip having a groove in one face thereof for the reception of said support, and the walls of said groove converging in the direction of its length.

3. The combination with a contact finger; of a burner tip having a substantially closed transverse recess accessible from one edge thereof, and a support carried by said contact finger and insertible in said recess.

4. The combination with a contact finger; of a support secured thereto, said support having inwardly beveled side edges, a burner tip carried by said support and having a groove in its inner face, the side walls of said groove being outwardly beveled toward the back thereof to receive said support, the thickness of said member being less than the depth of said groove, and the width of said support approximating the width of said groove at the back thereof.

5. The combination with a contact finger; of a wedge-shaped member secured thereto, the side edges of said wedge-shaped member being inwardly beveled to the inner face thereof, and a burner tip carried by said wedge-shaped member and having a wedge-shaped slot upon its inner face the side walls of which are outwardly beveled to the bottom thereof for the reception of said wedge-shaped member, the thickness of said wedge-shaped member being less than the depth of said slot, the width of said wedge-shaped member approximating the width of said groove at the back thereof, and means including a spring washer for clamping said wedge-shaped member to said finger.

6. The combination with a contact finger; of a support secured thereto, said support having inwardly beveled side edges, a burner tip carried by said support and having a groove in its inner face, the side walls of said groove being outwardly beveled toward the back thereof to receive said support, the thickness of said member being less than the depth of said groove, the width of said support approximating the width of said groove at the back thereof, and means including a spring washer for clamping said support to said finger.

In testimony whereof I affix my signature in the presence of two witnesses.

RAYMOND SWARTZ.
